DRILL WAGONS FOR USE IN TUNNELING
OR THE LIKEJan Patrik Danielsson, Stockholm, Sweden, assignor to
Atlas Copco Aktiebolag, a corporation of Sweden

Application August 23, 1951, Serial No. 243,339

Claims priority, application Sweden September 20, 1950

7 Claims. (Cl. 255—51)

This invention relates to drill wagons for use in tunneling or the like for driving comparatively small tunnel sections. A drill wagon according to the invention comprises a carriage movable on the ground, a driller's working platform carried by the carriage and movable lengthwise thereof from a position in which the platform is completely supported by the carriage to a position in which one end only of the platform is supported by the carriage and working space is provided for drillers below the platform, means for forming a support for the other end of the platform in the extended position of the platform, and means on the platform for forming seats for feed legs of rock drills at various distances from the extreme end of the platform. With the working platform completely supported by the carriage such a drill wagon may easily be transported to a working place and when blasting of the rock shall take place away from the working place. Drills, drill bits and other equipment used in connection with the tunneling work may be placed on the working platform and on the carriage in advance and may sometimes be connected in advance to suitable conduits for compressed air and pressure water provided in the carriage. All of the equipment necessary for drilling may consequently be forwarded to the working place by means of the drill wagon according to the invention in such a way that the equipment may immediately be used by the drillers.

In the accompanying drawings one embodiment of a drill wagon according to the invention is illustrated by way of example. Fig. 1 is a longitudinal section of a part of a tunnel with a drill wagon according to the invention in working position. Fig. 2 is a horizontal section of the same tunnel and a plan view of the drill wagon disposed therein. Fig. 3 is an end view and partial section on lines III—III in Fig. 1. Fig. 4 is a detail of a clamping device for clamping the drill wagon to a rail. Figs. 5 and 6 show details of the hinging of auxiliary platforms connected to a main working platform. Figs. 7 to 9 illustrate details of the guiding and supporting structure for the working platform.

The drill wagon illustrated on the drawings consists of a light rail carriage 1 having pairs of wheels 2 running on rails 3 in a tunnel, a frame structure 4 forming a cage with a trapezoidal cross section, and a driller's working platform 5. The working platform 5, which may preferably be disposed at a man's height, consists of spaced planking 6 secured to longitudinal beams 7. These beams are supported and guided by the upper side members of the frame structure 4 and rollers 8 journalled at one end of the frame structure 4. At the rear ends of both side beams 7 guide blocks 30 formed by short channel pieces, Figs. 8 and 9, are provided at the under side of the beams 7, said guide blocks embracing the upper flange of the channels forming the upper side members of the frame structure 4. The working platform is slideable lengthwise of the carriage on the frame structure from a position not illustrated in the figures in which the working platform is supported completely by the frame structure 4

2

to the position illustrated in the figures in which the working platform is extended from the frame structure and supported thereon at one end only. At the other end the working platform is provided with supporting means such as two extensible supporting legs 9 by means of which the working platform is supported at the free end, the right supporting leg only being illustrated in Fig. 3 whereas the left one is broken away. Lock bolts 10 are provided in the rear portion of the working platform, as is obvious from Figs. 1, 2 and 9 and may be moved into corresponding holes 27 in the upper side members of the frame structure 4 so that the working platform may be locked in extended position as well as in the position in which it is supported completely by the substructure. In working position as well as in transportation position the working platform is thus prevented from moving relative to the frame structure. The carriage 1 has a rail clamping means 11 provided thereon which consists of two jaws 12 capable of grasping the head portion of the rail, and a locking ring 13 by means of which the jaws may be locked onto the head portion of the rail, as illustrated in Fig. 4.

Conduits 14, 15 for compressed air and pressure water, respectively, are provided in the carriage 1 these conduits leading to tapping points 16, 17 below the platform level at the lower front end of the substructure and tapping points 18, 19 at the platform level secured at the rear portion of the working platform 5 by brackets (not illustrated). The hoses of the drills 20, 21 may be connected to these tapping points. Upon driving a tunnel of the size for which the drill wagon according to the invention is intended two drills may, for instance, be provided on the working platform 5 and two drills on the ground so that four drills may be operated simultaneously for drilling the holes necessary for blasting the intended tunnel section. The lower ends 28 of the feed legs of the drills find seats against the planking 6 in the spaces 25 between the planking. During transportation the drills may be disposed on the carriage and on the working platform where other necessary equipment such as drill bits or the like may also be carried. The whole equipment necessary for drilling and blasting may according to the invention be carried on the drill wagon. As soon as the working front is ready for drilling the drill wagon is forwarded to the working front where the equipment is immediately brought into operation. When drilling is finished the drill wagon is moved away from the working front so that blasting and removal of the loose rock may take place. At a suitable distance from the working front a cave is provided in the side wall of the tunnel in which cave the drill wagon may be moved in order to provide free passage for the transports of the loose rock.

In the illustrated embodiment the working platform is provided with leaves 22 at the sides by means of which the area of the working platform may be increased sideways and which are secured to the working platform by means of hinges 23 (see Figs. 2, 5 and 6). In swung out position the leaves are supported by bars 24 movable in suitable holes in the beams 7 and of such length that they do not project materially outside the confines of the platform 5 in retracted position of the bars 24. Members 26 on the leaves 22 form supports or seats against which the feed legs of the drills rest during drilling from the leaves.

The drill wagon above described and illustrated in the drawings should only be considered as an example, and the invention may be modified in several different ways within the scope of the claims. Pneumatic or mechanical horizontal jacks or extensible members may be provided on the platform for stabilizing the platform sideways by engaging the side walls of the tunnel, one such jack only being illustrated in Fig. 3 swingable on a bolt 32 project-

ing forwardly at the upper end of the jack 9. The working platform may be provided with one supporting leg instead of two, as illustrated in Figs. 1 and 3, or with an extensible column which may be pressed towards the walls, the bottom and/or the roof of the tunnel for supporting the free end of the working platform. The drill wagon may be provided with pneumatic tires, runners or the like for enabling movement of the drill wagon on the ground.

What I claim is:

1. A drill wagon for driving tunnels in rock or similar material comprising a framework of about a man's height and of trapezoid cross section having traction wheels mounted at the small side of said cross section, a driller's working platform slidably mounted on said framework at about a man's height and at the large side of the cross section and movable from a retracted position over said framework to an extended position outwardly of the framework with one end only supported on the framework, means at the opposite end of said working platform for engaging the rock to support said opposite end, extension platforms at the sides of the working platform movable from a position substantially within the horizontal area of said slidably mounted working platform to positions extending from the sides of said slidably mounted working platform, means for locking the working platform in extended position relative to said framework, abutment means on said platforms for foot pieces of drill feed legs, and means for taking up the reaction from drilling and feeding the drills on the platform through said abutments.

2. A means for driving tunnels in rock or similar material comprising a framework of about a man's height forming a rigid cage having traction wheels mounted at the under side and a driller's working platform slidably mounted in the upper portion at about a man's height and movable from a retracted position over said framework to an extended position outwardly of the framework with one end only supported on the framework, means at the opposite end of said working platform for engaging the rock to support said opposite end, pusher leg mounted drills below and on said extended working platform, compressed air and flushing water connections for said drills on said framework, abutment means on said working platform for a foot portion of said pusher legs, and means for taking up the reaction from drilling and feeding the drills on the platform through said abutments.

3. A drill wagon for tunneling in rock or the like by means of pusher feed leg mounted drills and comprising a carriage of about a man's height having a driller's working platform slideable horizontally and longitudinally of said carriage at about a man's height above the level on which said carriage is movable, said platform providing abutment means for taking up the reaction from said pusher feed legs during feeding and drilling from said platform, and means for taking up the reaction from drilling and feeding the drills on the platform through said abutments.

4. A drill wagon for driving tunnels or the like and comprising a carriage movable on the ground which in operating position provides a first drill runner's working space on the ground and a second drill runner's working space just above said first space, a drill runner's working platform carried by said carriage and movable lengthwise of the carriage from a position in which said platform is completely carried on the carriage to a position in which one end of the platform only is supported by the carriage and said first drill runner's working space is provided below the platform, expandable supporting means on the platform for forming a support of the other end of the platform in extended position of the platform, means on the platform at various distances from the extreme end of the platform for forming seats for a foot piece of a feed leg of a rock drill, compressed air and flushing water distribution systems in the carriage ar-

ranged for connection to compressed air and flushing water supply conduits in a tunnel or the like, and a plurality of tapping couplings on said distribution system for connection of a plurality of rock drills.

5. A drill wagon for tunneling in rock or the like comprising a carriage, supporting wheels on said carriage, a working platform slidably mounted on said carriage and movable from a retracted substantially centered position over said carriage to an extended working position outwardly of said carriage with one end only supported on said carriage, rollers on said carriage for supporting said one end, extensible means on the opposite end of said platform for engaging the rock to support said opposite end, means for locking said platform in retracted or extended position, extension platforms hingedly mounted on the sides of said working platform and movable from a position overlying the working platform to an extended position whereby the width of the working platform may be varied, means for slidably carrying supporting bars in the working platform, bars slidably mounted in said means to extend below the extension platforms for supporting the same in extended position, said bars being retractable in said means within the confines of the working platform when the extension platforms are in position on the working platform, spaced means on the working platform and the extension platforms providing abutments for a foot piece of a drill feeding means of the pusher leg type, and means for preventing movement of said carriage during drilling operations.

6. A drill wagon for tunneling in rock or the like comprising a carriage, supporting wheels on said carriage, a working platform slidably mounted on said carriage and movable from a retracted substantially centered position over said carriage to an extended working position outwardly of said carriage with one end only supported on said carriage, rollers on said carriage for supporting said one end, extensible means on the opposite end of said platform for engaging the rock to support said opposite end, means for locking said working platform in retracted or extended position, extension platforms hingedly mounted on the sides of the working platform and movable from a position overlying the working platform to an extended position whereby the width of the working platform may be varied, means for slidably carrying supporting bars in the working platform, bars slidably mounted in said means to extend below said extension platforms for supporting the same in extended position, said bars being retractable in said means within the confines of the working platform when the extension platforms are in position on the working platform, and spaced means on the working platform and the extension platforms providing abutments for a foot piece of a drill feeding means of the pusher leg type.

7. A drill wagon for tunneling in rock or the like comprising a carriage, supporting wheels on said carriage, a working platform slidably mounted on said carriage and movable from a retracted position over said carriage to an extended working position outwardly of said carriage with one end only supported on said carriage, extensible means on the opposite end of said platform for engaging the rock to support said opposite end, extension platforms hingedly mounted on the sides of said working platform and movable from a position overlying the working platform to an extended position whereby the width of the working platform may be varied, means for slidably carrying supporting bars in the working platform, bars slidably mounted in said means to extend below said extension platforms for supporting the same in extended position, said bars being retractable in said means within the confines of the working platform when the extension platforms are in position on the working platform, spaced means on the working platform and the extension

platforms providing abutments for a foot piece of a drill feeding means of the pusher leg type, and means for taking up the reaction from drilling and feeding of drills on the platforms through said abutments.
